UNITED STATES PATENT OFFICE.

ERNESTE ROTHLSBERGER, OF CINCINNATI, OHIO.

TOP-PROP NUT.

SPECIFICATION forming part of Letters Patent No. 313,772, dated March 10, 1885.

Application filed May 29, 1884. (No model.)

To all whom it may concern:

Be it known that I, ERNESTE ROTHLSBERGER, a citizen of the United States, and a resident of Cincinnati, in the county of Hamilton 5 and State of Ohio, have invented certain new and useful Improvements in Carriage-Top Bolt-Heads, of which the following is a specification.

My invention relates to the manufacture of 10 bolt-heads adapted to be used for carriage-tops and other similar purposes.

The object of my invention is to furnish a 15 cheap ornamental leather-finished bolt-head, which may be screw-threaded and used as a prop-nut, or may be permanently attached to the shank of the bolt, as desired, all of which will be fully set forth in the description of the accompanying drawings, in which—

Figure 1 is a top plan view of my improved 20 bolt-head. Fig. 2 is a vertical cross-section showing the same screw-threaded. Fig. 3 is a vertical cross-section of the molding. Fig. 25 4 is a plan view of the finished or ornamental portion of the head. Fig. 5 represents a metallic stiffening-blank. Fig. 6 shows the bolt-head permanently attached to the shank.

A represents a metallic shank, which is provided with a circular concave head, *a*.

B represents a molding, which is struck up 30 from an annular sheet-metal blank, first into the form shown in Fig. 3.

b represents the horizontal portion of the molding, which covers the outer peripheral edge of the bolt-head.

35 *c* represents a vertical flange.

C represents a circular piece of finished leather or other fibrous material of sufficient size to fit within the vertical flange *c*.

D represents a concave metallic blank, which 40 is used as a stiffening to support and hold the leather in its position. After the blank D has been struck up to the form shown in Fig. 3, the leather *C* is placed within the cup of flanges *b c*, the finished side uppermost. This

stiffening metallic blank D is placed against 45 the leather. This is made concave or cup-shaped, so that its outer edge will rest upon the upper side of the shank-head *a*, and the concave portion will hold the leather firmly in the desired form. The head of shank *a* is 50 placed within the molding-flange *c*, which flange is then spun or turned down upon the under side of the flange *a* of the head of the shank, the molding *b c* firmly holding the parts A B C D together to form the bolt-head. 55 When this bolt-head is desired to be used as a nut, the shank is pierced and tapped with screw-threads E to engage with the threads of the bolt to which the head is to be applied. When this bolt-head is not designed to be used as a tap, the shank A is made solid, as shown in Fig. 6, in which form it is used as a bolt or rivet. The molding *b* may have imitation stitches struck up upon its inner periphery, so as to imitate leather-stitching, as 60 shown in Fig. 1.

I claim—

1. A bolt-head for carriage-tops combining in its structure a shank, A, having the head *a*, the disk D, resting on the head, the covering C upon the disk, and the molding B, overlying the edge of the covering and secured to the head, substantially as described. 70

2. A bolt-head for carriage-tops consisting of the following elements, to wit: the shank 75 A, having the circular head *a*, the concavo-convex disk D, resting at its edge on the head, the flexible covering C on the disk, and the molding B, having the flanges *b* overlying the covering and the flange *c* underlying the head, 80 substantially as described.

In testimony whereof I have hereunto set my hand.

ERNESTE ROTHLSBERGER.
